Specification of Letters Patent.

Patented Apr. 1, 1913.

Application filed March 29, 1912. Serial No. 686,987.

To all whom it may concern:

Be it known that I, ELIAS PALTER, a citizen of the United States, and a resident of the city, county, and State of New York, 5 have invented certain new and useful Improvements in Thimbles, of which the following is a specification.

The principal object of my invention is to provide a thimble that will not drop, 10 slip or be forced off the finger, when in use during the operation of sewing, and that will be comfortable.

The ordinary thimble is conical interiorly and exteriorly, its interior being smooth 15 and tapering from its open base to its top. If the thimble be too small or even if it fits the finger tightly enough to stay on well, it will be uncomfortable, and retard the circulation; if it be too large, it will be likely 20 to drop off, and the person using it will be constantly endeavoring to keep it on. Under every condition, the least pressure on the ordinary thimble in a direction from its base toward the tip of the finger, will cause 25 it to loosen on the finger, and to drop off the same, and there will be the same tendency upon a movement of the hand, when the closed end of the thimble is below its open end. Moreover, the ends of some 30 fingers are tapering, and some are not. With those that are not, the ordinary thimble will fit closely only near its smaller closed end, while the rest of the thimble will be loose on the finger, so that it will take 35 very little to cause the thimble to drop off.

My invention overcomes all the above mentioned difficulties.

The accompanying drawing illustrates one embodiment of my invention, in 40 which—

Figure 1 is a longitudinal section of the thimble, its proper position when in use on a finger being indicated by the finger shown in dotted lines. Fig. 2 is an end view of the 45 thimble looking into its open end from the base. Fig. 3 illustrates the thimble in its proper position on a finger, showing the inside of the finger and the back portion of the thimble. Fig. 4 illustrates the positions 50 the fingers of a hand assume during a portion of the action of sewing, the thimble being shown in its proper position on the middle finger.

Similar characters represent like parts in 55 all the figures.

1 is the open base of the thimble, and 2 is its opposite end.

3—3 are recesses in the inner wall of the thimble near its base, and as shown in the drawing, said recesses consist of transverse 60 openings extending through said wall. The edge of the base beyond the recesses or openings 3—3 extends inward toward the opposite portion of the edge, and said extending portion is a tongue 4 having op- 65 positely projecting arms 5, the inner edges of which, or those nearest the base, extending in a continuous direction transverse to the thimble, and constituting portions of the edges of the openings 3. 70

The thimble when in the proper position on the finger should have the tongue portion 4 extending across and bearing upon the inside of the finger, and the inwardly pro- 75 jecting edge of said tongue above the apex of the swell of the joint, or near the crease of the joint, as shown in Figs. 1, 3 and 4.

The slight pressure on the thimble near its base 1 tends to force a little of the flesh of the finger into the recess 3, as shown at 80 6—6, Figs. 3 and 4. When the finger is bent in the operation of sewing, there will be a slight additional forcing of the flesh into said recess, and the overlapping of the edges 7 of the projections 5 will bear upon 85 the flesh 6 that had been forced into the recesses, and prevent the thimble from dropping off the finger.

In the operation of sewing, the first and third fingers 8 and 9 of the hand are very 90 apt to rub against the thimble on the middle finger 10, (see Fig. 4), and when this rubbing is in a direction toward the end 2 of the thimble, it would be likely to force the thimble off the finger 10. This is especially 95 so if the thimble is too large for the finger, or if the finger is not conical. The edges 7, however, of my improved thimble, and the inwardly extended portion 4 of the edge of the base 1 will prevent the thimble from 100 falling off. By the use of my invention the thimble need not fit the end of the finger tightly, it being only necessary to have a slight pressure near the base of the thimble upon the finger. With the ordinary thimble, however, in order to get satisfactory results in sewing, the thimble should fit the finger quite tightly, and this tends to retard the circulation, which result my improved 105 thimble avoids. 110

It will be obvious that my invention is not limited to the precise thimble shown in the drawings and described in the specification.

5 What I claim as new, and desire to secure by Letters Patent, is:—

1. A thimble having a recess in its inner wall near its open base, the edge of said recess nearest said base extending in a continuous direction transverse to the thimble, and a part of the edge of said base projecting inward toward the opposite edge of the thimble.

15 2. A thimble having a plurality of recesses in its inner wall near its open base, the edges of said recesses nearest said base extending in a continuous direction transverse to the thimble, and a tongue forming part of the edge of said base projecting inward toward the opposite edge of the thimble and from a point between and below two of said recesses.

20 3. A thimble having a transverse opening

in its wall near its base, the edge of said opening nearest said base extending in a continuous direction transverse to the thimble, and a part of the edge of said base projecting inward toward the opposite edge of the thimble.

25 4. A thimble having a plurality of transverse openings in its wall and near its base, the edges of said openings nearest said base extending in a continuous direction transverse to the thimble, and a tongue forming part of the edge of said base projecting inward toward the opposite edge of the thimble and from points between and below two of said transverse openings.

30 In testimony whereof, I have signed my name to this specification, in the presence of 40 two subscribing witnesses.

ELIAS PALTER.
